(57) CLAIM

I claim the ornamental design for a kitchen tool, as shown and described.

DESCRIPTION

FIG. 1 is a top perspective view of a kitchen tool;
FIG. 2 is a bottom perspective view of a kitchen tool;
FIG. 3 is a top plan view of a kitchen tool;
FIG. 4 is a bottom plan view of a kitchen tool;
FIG. 5 is a front elevation view of a kitchen tool, the back elevation view being identical to the front elevation view; and,
FIG. 6 is a side elevation view of a kitchen tool, both sides being the same.
